FOLDING METAL CHICKEN CRATE

John F. Lease, Pico, Calif., assignor of one-half
to Glee Hanson Barnes, Pico, Calif.

Substituted for abandoned application Serial No.
53,064, December 5, 1935. This application
April 19, 1944, Serial No. 531,845

4 Claims. (Cl. 220—7)

This invention which formed the basis of abandoned application Serial No. 53,064, filed Dec. 5, 1935, relates to a folding or collapsible metal chicken crate, and it aims to provide an exceedingly durable and relatively inexpensive construction which may be readily collapsed or extended and in which the parts are held in extended position by means of springs and associated latch members, all remaining permanently attached to the crate parts.

The more specific objects and advantages will become apparent from a consideration of the description following taken in connection with accompanying drawings illustrating an operative embodiment.

In said drawings—

Figure 1 is a plan view of the crate;

Figure 2 is a side elevation of the crate;

Figure 3 is a longitudinal sectional view, taken substantially centrally through the crate and showing a cover wall or panel raised;

Figure 4 is a longitudinal sectional view taken on the line 4—4 of Figure 1;

Figure 5 is a cross sectional view taken on the line 5—5 of Figure 4;

Figure 6 is a view taken on the same plane as Figure 5, but with the parts collapsed;

Figure 7 is a horizontal sectional view taken on the line 7—7 of Figure 2; and

Figure 8 is a horizontal sectional view taken on the line 8—8 of Figure 2.

Referring specifically to the drawings wherein like reference characters designate like or similar parts, 10 designates a bottom wall preferably metallic and in pan form. It is imperforate and has standing side flanges 11 and end flanges 12. If desired, one or more battens of wood, metal, or other material, may be secured to the under surface of the bottom 10, as at 10'.

The crate also has two end walls 13, two side walls 14, two top walls 15, and a partition wall 16. Said walls 13, 14, 15, and 16 are constructed so as to occupy the extended position best shown in Figures 1, 2, 4, and 5, or to be collapsed into the condition shown in Figure 6.

The walls 13 and partition 16 are similar in construction. They consist of transverse rods 18 spanning and journaled in the flanges 11, and which have the free terminals of U-shaped frames 19 of angle cross section rigidly fastened thereto. In addition, crossed metallic wires 20 are soldered or otherwise fastened to each other at the points of crossing and soldered or otherwise fastened to rods 18 and flanges of the angle frames 19. These walls 13 and 16 may be folded

into the pan 10 into parallelism therewith when not in use, and when in use, occupy a vertical position.

Each of said walls 13 and 16 includes a contractile coil spring 21, having one end 22 anchored to the rods 18 and having a latch rod 23 connected to the opposite end of the spring, and which pass loosely through openings 24 in flanges of the angle frames 19. The upper ends of said latch rods 23 have downwardly extending hooks 25 on opposite sides thereof.

The side walls 14 are similar in construction. Each side wall has a longitudinal rod 27 at the base thereof journaled in the flanges 12 of the base wall. Rigid with rods 27 at each end thereof are right angularly disposed angle members 28, which are connected at the end opposite the rods 27 by a rod 29 parallel with the rod 27 and rigidly secured at opposite ends to the angle members 28. Cross wires 30 are soldered or otherwise rigidly secured together at the points of crossing and soldered or otherwise rigidly secured at their respective terminal ends to the angle members 28 and rods 27 and 29.

It will be noted that the rods 27 are disposed above the position occupied by the walls 13 and 16 in their folded position, and hence the walls 14 may be folded over and superposed on the walls 13 and 16.

It will be noted that in the folded condition of the crate, the top walls 15 are in the same plane with the walls 14 to which they are attached. Such top walls consist of longitudinal rods 31 and end bars 32 rigidly connected to said rods 31 and journaled on the rods 29. In addition, said top walls 15 have cross wires 33 soldered or otherwise rigidly connected together at the points of crossing, and soldered or otherwise rigidly connected with their respective terminals to the rods 31 and bars 32. Those ends of wires 33 adjacent the rods 29 are hook-shaped, extending about the rods 29 and being journaled thereon. When the various walls are in the extended or operative position, they are fastened against collapse through the engagement of the hooks 25 with the rods 31 as shown, such engagement being readily effected since the latch members 24 may be moved against the tension of the springs 21.

Various changes may be resorted to provided they fall within the spirit and scope of the invention, and for instance, a closure or closures may be provided in any of the various walls to facilitate the placing or removal of chickens or the like within the crate.

Obviously, the crate is not limited to use as a chicken coop, but may be employed for any purpose desired.

I claim as my invention:

1. A crate of the class described, having a bottom wall provided with upturned side flanges and end flanges, end walls disposed between said flanges having U-shaped frames providing downwardly extending bars and a connecting bar at the top thereof, rods journaled in the side flanges on which the lower ends of said downwardly extending bars are journaled, said end walls being collapsible against the bottom wall, side walls having rods, the latter rods being disposed above the folded position of the end walls and journaled in the end flanges, said side walls being foldable over said end walls, top walls carried by the side walls and foldable over said end walls, latches slidably mounted in said connecting bars engageable with the top walls to prevent collapse of the crate, and contractile spring means connected to said latches and to the rods journaled in the side flanges.

2. A crate of the class described, having a bottom wall provided with upturned side flanges and end flanges, end walls disposed between said flanges having rods journaled in the side flanges, said end walls being collapsible against the bottom wall, side walls having rods, the latter being disposed above the folded position of the end walls and journaled in the end flanges, said side walls being foldable over said end walls, top walls carried by the side walls and foldable over said end walls, frames on the end walls, latches slideable in said frames engageable with the top walls to prevent collapse of the walls, contractile spring means connected to said latches and to the rods of the associated wall, and a plurality of hooks on said latches.

3. A crate of the class described, having a bottom wall provided with upturned side flanges and

end flanges, end walls disposed between said flanges provided with bars which are pivoted to rods journaled in the side flanges, said end walls being collapsible against the bottom wall, side

5 walls having rods, the latter being disposed above the folded position of the end walls and journaled in the end flanges, said side walls being foldable over said end walls, top walls carried by the side walls and foldable over said end walls, latches carried by the end walls engageable with the top walls to prevent collapse of the walls, contractile spring means connected to the rods which are journaled in the side flanges and to said latches, all of said walls comprising primarily crossed 10 wires in frame members at the edges of the walls, rods at the upper ends of the side walls, the top walls having bars at the ends thereof which are pivoted to the rods at the upper ends of the side-walls, and wires of the top walls having hook 15 shaped portions surrounding and journaled on the last mentioned rods.

20 4. A crate of the class described, having a bottom wall provided with upturned side flanges and end flanges, end walls disposed between said flanges having rods journaled in the side flanges, said end walls being collapsible against the bottom wall, side walls having rods, the latter rods being disposed above the folded position of the end walls and journaled in the end flanges, said 25 side walls being foldable over said end walls, top walls carried by the side walls and foldable over said end walls, latches carried by the end walls engageable with the top walls to prevent collapse of the walls, contractile spring means connected to said latches and to the rods of the associated wall, a plurality of hooks on said latches, a partition wall having a rod pivoted to the side flanges, and contractile spring controlled latch means 30 carried by the partition wall and engageable with the top walls.

JOHN F. LEASE.
